UNITED STATES PATENT OFFICE.

GEORGE M. COKE, OF MILWAUKEE, WISCONSIN, ASSIGNOR TO THE FULLER-WARREN CO., OF MILWAUKEE, WISCONSIN, A CORPORATION OF WISCONSIN.

COOKING-RANGE.

1,296,626.

Specification of Letters Patent. Patented Mar. 11, 1919.

Application filed October 26, 1914. Serial No. 868,570.

To all whom it may concern:

Be it known that I, GEORGE M. COKE, a citizen of the United States, residing at Milwaukee, in the county of Milwaukee and State of Wisconsin, have invented certain new and useful Improvements in Cooking-Ranges, of which the following is a specification, reference being had to the accompanying drawing, forming a part thereof.

10 The main objects of this invention are to construct a cooking stove or range for the economical and convenient use of either gas or solid fuel such as coal, coke or wood; to provide for the use of either kind of fuel 15 without interfering with the proper operation or efficiency of the range or stove with the other kind; to facilitate changing from one kind of fuel to the other; and generally to improve the construction and operation 20 of ranges or stoves of this class for using fuel of different kinds.

It consists in the peculiar construction, arrangement and combination of parts as hereinafter particularly described and pointed 25 out in the claims.

In the accompanying drawing like characters designate the same parts in the several figures.

Figure 1 is a longitudinal vertical section 30 in a plane indicated by the broken line 1-1, Fig. 2, of a range embodying the invention; Fig. 2 is a horizontal section of the same in a plane indicated by the broken line 2-2, Fig. 1; Fig. 3 is a vertical cross section in 35 a plane indicated by the broken line 3-3, Fig. 1; and Fig. 4 is an inverted plan view of the removable oven plate and gas burner.

Referring to Figs. 1, 2 and 3, the range 40 comprises an oven *a*, a fire box *b*, and an ash pit *c* below the fire box at one side of the oven, and a flue *d*, leading from the upper part of the fire box, over, down the opposite side of and underneath the oven.

45 The range is provided at the back with the usual vertical smoke flue *e*, with which the upper and lower parts of the oven heating flue *d* communicate through openings *f* and *g*, the upper opening *f* being provided 50 with a damper *h*, as indicated by dotted lines in Fig. 3, for producing a direct or indirect draft in the usual manner in ranges designed for using solid fuel such as coal, coke or wood.

55 The construction of the range as thus far

described, is substantially like that of ordinary coal ranges except that the top plate *i*, which is provided over the fire box and oven with the usual pot openings and covers (not shown), is extended beyond the oven at the opposite side from the fire box, and is provided with open-work grids or grilles *j*, for gas burners *k*, which may be constructed and arranged as in ordinary gas ranges. The top oven plate *l* is also curved 60 or bent downwardly in conformity with the plate *m* below the gas burners, to provide for the requisite flue space over the oven, and the range is made of somewhat greater height than is customary in coal ranges, to 65 allow for the downwardly curved or bent upper portion of the flue *d* and at the same time provide for an oven of the desired height.

To adapt the range to use gas for heating 70 the oven without encroachment upon the flue *d* and without reducing the efficiency and convenience of the range when coal or other solid fuel is used, the following changes in and additions to the construction of the 80 range besides those above mentioned, are made:

A plate *n*, provided on the under side with a gas burner *o* and with legs or supports *p*, removably fitted in the oven above 85 and parallel with its bottom on which the legs or supports *p* are adapted to rest, and when placed in position in the oven, forms a combustion chamber *q* in the lower part thereof for the burner, the range being provided on the front side with a wide door *r*, having a glazed or mica covered opening *s* opposite the combustion chamber for observing and regulating the operation of the 90 burner.

95 As shown in Figs. 2 and 4, at or adjacent to its opposite edges the plate *n* is formed with openings *t*, and is cut away at the rear and front edges to afford communication between the combustion chamber and the oven above it, and to allow the heated air and mingled products of combustion from the burner to pass upwardly from the combustion chamber into and circulate through the oven.

100 The side wall of the oven next to the vertical portion of the flue *d* is formed with vent openings *8*, through which the waste gases and products of combustion from the burner escape from the oven into said flue, 105 110

thus avoiding their interfering with the proper operation of the burner.

The burner o is preferably made of tubular form with jet openings or orifices in opposite sides thereof, and is disposed obliquely to the plate n , so that the flames produced by the burner will spread and cover the under side of the plate, or a large portion thereof.

10. The rear end of the burner, which projects beyond the rear edge of the plate n , has an enlarged opening and is made parallel with the side edges of the plate so that it will pass freely through an opening in the 15 rear wall of the oven, as shown in Figs. 2 and 3.

At the back of the range an air chest or duct u is formed or provided, having an intake opening at its upper end which is normally closed by a valve v . At its lower end this chest or duct communicates through openings in the back plate of the oven and range with a duct w , which in turn communicates at its upper end through openings 25 in the bottom plate of the oven with the combustion chamber q when the plate n is in position. When the burner is placed in position in the oven the opening in its rear end is within the air chest or duct u in position 30 to receive air therefrom.

The valve v is provided on its under side with an arm or projection x which by engagement with the end of the burner as it is inserted in position, lifts and opens the 35 valve, as shown in Fig. 3.

A branch pipe y taken off from the pipe z which supplies the top burners k , leads around the end of the range, as shown in Fig. 2, and is provided at its end with a nipple 40 2, projecting into the air chest u in position to enter the open end of the burner o when it is placed in position, leaving a space around it for the admission of sufficient air to produce the proper mixture in the burner.

45 The pipe y is provided with a cock 3, which is easily accessible from the front of the range and controls the supply of gas to the oven burner.

In addition to the air entering the combustion chamber q through the ducts u and w , the requisite supply for the operation of the burner is provided by ducts 4, leading upwardly from openings in the bottom plate of the range through the ash pit c and openings in the adjacent oven wall into the combustion chamber q . The openings at the upper ends of these ducts are provided with valves 5, which normally close them, these valves as well as the valve v , being self-closing, or closing by gravity when they are released.

The valves 5 are formed or provided with arms or projections 6, which extend through the openings in the oven wall, and by engagement with inclines 7 on the under side

of the plate n , open the valves when the plate is inserted in the oven, as shown in Figs. 1 and 2.

As shown in Figs. 1, 2 and 3, the range is in condition for using gas to heat the oven. 70

In the operation of the oven with the gas burner, air supplied through the chest or duct u to the rear open end of the burner, mingles with the gas supplied through the nipple 2, to produce the requisite mixture. 75 The auxiliary or secondary supply of air required to produce proper combustion of the gas as it issues from the jet orifices of the burner into the chamber q , is supplied through the air chest u and duct w at the 80 back of the oven, and through the ducts 4 at one side of the oven. The hot waste gases produced by the burner, mingled with the air supplied to and heated in the combustion chamber q , pass upwardly through the openings t at the sides, and the openings at the rear and front edges of the plate n into the oven a above the plate, and the products of combustion escape from the oven through the vent openings 8 into the flue d , by which 90 they are conducted into the smoke flue e .

The burner is lighted by opening the oven door r and applying a match or lighter to its front end. It is regulated by means of the cock 3, while its operation is observed 95 through the opening s .

To change the range for heating the oven with coal or other solid fuel in the fire box b , all that is required is to open the oven door r , and withdraw the plate n , the valves 100 v and 5 closing automatically and preventing the admission of air into the lower part of the oven and interfering with its proper operation.

The air chest or duct u and the ducts 4, 105 being located entirely outside the oven walls, do not encroach upon the flue d or in any wise interfere with the proper operation of the range and oven when coal or other solid fuel is used in the ordinary manner. 110

Various changes in the construction and arrangement of parts of the range may be made without affecting its principle or mode of operation and without departure from the invention as defined in the following 115 claims:

I claim:

1. In a cooking range the combination with an oven having an opening in the back wall adjacent the bottom, of a self-closing 120 valve controlling the admission of air through said opening into the oven, a gas supply pipe outside the oven adjacent said opening, a removable plate insertible through the door-way of the oven and fitted in the 125 oven above and parallel with its bottom and adapted to form therewith a combustion chamber, and a burner attached to the under side of and removable with said plate and adapted when placed in working position in 130

the oven to open said valve and to make operative connection with the gas supply pipe.

2. In a cooking range the combination with an oven having an opening in the back 5 wall adjacent the bottom, of a gas supply pipe outside the oven adjacent to said opening, a removable plate insertible through the door-way of the oven and fitted in the oven above and parallel with its bottom and 10 adapted to form therewith a combustion chamber in communication with the upper part of the oven, a self-closing valve controlling the admission of air through said opening into the oven, and a burner attached to 15 the under side of and removable with said plate and adapted when inserted in the oven to stand in operative relation to the gas supply pipe and to open said valve and admit outside air into said combustion chamber 20 and into the burner itself.

3. In a cooking range having an oven, a fire box at one side of the oven, and a flue leading from the fire box over, down one side of and underneath the oven, a plate insertible through the door-way of the oven and fitted in the oven parallel with the bottom thereof and forming therewith a combustion chamber, an air chest opening into the oven and having an air inlet opening, a valve for 25 closing said inlet opening, a burner attached to and removable with said plate and adapted when placed in working position to open said valve and receive air from said chest, and a gas supply pipe with which the burner 30 is brought into operative relation when it is placed in working position in the oven.

4. In a cooking range the combination with an oven, a fire pot at one side of the oven and a flue leading from the fire box 40 over, down one side of and underneath the oven, of a plate insertible through the door-way of the oven and fitted in the oven parallel with the bottom thereof and forming therewith a combustion chamber, an air 45 chest communicating with the oven below said plate and having an air inlet opening, a valve for closing said opening, a gas supply pipe having a nipple projecting into the air chest opposite an opening in the oven wall, 50 and a burner attached to the under side of and removable with said plate and adapted when placed in position in the oven to pass

at its open intake end through said oven wall opening into said chest in operative relation to said nipple, air being supplied from 55 said chest to the burner and the combustion chamber outside of the burner.

5. In a cooking range the combination with the oven, of an air chest having an air inlet and communicating with the oven 60 through an opening in the intervening wall, a valve for closing the air inlet of said chest, a removable plate insertible through the door-way of the oven and fitted in the oven and forming a combustion chamber in the 65 lower part thereof, a gas burner attached to and removable with said plate and adapted when placed in position to project through the opening in the oven wall into said chest and to open said valve, and a gas supply pipe 70 leading into said chest and adapted to loosely connect with the burner when it is placed in operative position in the oven.

6. In a cooking range the combination with the oven, a fire box at one side thereof, 75 an ash pit below the fire box, and a flue leading from the fire box over, down one side of and underneath the oven, of an air supply duct leading upwardly through the ash pit into the lower part of the oven at one side 80 thereof and provided with a self-closing valve, an air chest at the back of the range communicating with the oven and having an intake opening provided with a self-closing valve, a plate removably fitted in the oven 85 above the openings into it from said duct and chest and provided on the under side with a gas burner, which communicates at one end when in working position, with said air chest, the oven communicating with said 90 flue above said plate through a vent opening and said plate and burner being adapted when inserted into place in the oven to open said valves, and a gas supply pipe leading into said air chest and adapted to loosely 95 connect with the burner when it is placed in working position.

In witness whereof I hereto affix my signature in presence of two witnesses.

GEORGE M. COKE.
